Patented May 7, 1912.

UNITED STATES PATENT OFFICE.

JOHN H. PROCTOR, OF MINNEAPOLIS, MINNESOTA.

MARKING AND GROOVING TOOL.

1,025,302.

Specification of Letters Patent.

Patented May 7, 1912.

Application filed December 30, 1911. Serial No. 668,754.

To all whom it may concern:

Be it known that I, JOHN H. PROCTOR, a citizen of the United States, residing in Minneapolis, in the county of Hennepin and 5 State of Minnesota, have invented certain new and useful Improvements in Marking and Grooving Tools, of which the following is a specification.

My invention primarily relates to tools 10 for marking and grooving imitation tile or hard wall plaster finish, and it consists in a tool so shaped and constructed that it may be used for marking and grooving in an easy and expeditious manner.

15 In the accompanying drawings:—Figure 1 shows my improved tool, and indicates how it is used for marking. Fig. 2 is a similar view showing how the tool may be used for making grooves when the grooves are 20 relatively narrow and deep. Fig. 3 shows how the tool may be employed for making relatively shallow and wide grooves. Fig. 4 is a detail view, in section, of a part of a wall showing the kind of mark made by the 25 tool. Fig. 5 is a similar view, showing the form of the groove produced by the tool when used as indicated in Fig. 2. Fig. 6 is a similar view, showing the form of the groove produced in the manner indicated in 30 Fig. 3. Figs. 7, 8 and 9 are sectional views on the lines 7—7, 8—8 and 9—9 of Fig. 3.

The tool A is made of one piece of metal, and preferably has a wooden handle B. The shank a is connected with the handle in the 35 manner indicated in Fig. 3, and from the shank projects diagonally an arm c connecting with a grooving portion d of the cross section shown in Fig. 7. From the outer end of the grooving portion d extends an 40 arm e approximately parallel with the arm c and from which extends outwardly and forwardly in a diagonal direction a marking finger f, which is beveled in the manner clearly indicated in Figs. 3 and 9.

For marking with this tool, the point or 45 end of the finger is used, as indicated in Fig. 1. Any straight edge may be used in connection with the tool for producing this mark. In order to form a relatively deep and relatively narrow groove, the edge of 50 the portion d is employed, as indicated in Fig. 2; but when a relatively wide and relatively shallow groove is desired, the tool is used as indicated in Fig. 3, and when so used the width of the groove may be varied 55 by giving the proper inclination to the tool when being drawn along the mark.

This tool may be made of any desired size. It can be used either from the right or left, and the surface being marked off is always 60 in plain sight of the user. It clears the user's hands from the wall upon which it is being used, and is of such shape as to make its use easy and comfortable.

I claim as my invention:

1. A marking and grooving tool, provided with a relatively long and narrow beveled grooving portion, an arm at the outer end of said grooving portion, and a tapered finger extending diagonally outward from the outer 70 end of said arm having a pointed end with beveled edges.

2. A marking and grooving tool, having parallel arms and a straight beveled grooving portion connecting the arms, and a 75 marking and grooving tapered finger extending diagonally outward from the end of one of the arms and which has a pointed beveled end.

In testimony whereof, I have hereunto 80 subscribed my name.

JOHN H. PROCTOR.

Witnesses:

MATT H. WITLICH,
HARRY A. GUTEY.
